UNITED STATES PATENT OFFICE

PAUL RUNNELS, OF INDIANAPOLIS, INDIANA, ASSIGNOR, BY MESNE ASSIGNMENTS, TO INDUSTRIAL SOLVENTS, INC., OF INDIANAPOLIS, INDIANA, A CORPORATION OF INDIANA

LIQUID CONTAINER

Application filed April 17, 1930. Serial No. 444,956.

My invention is concerned with a device suitable for use in removing dirt or stains from fabrics by the application of one of the usual cleaning fluids such as carbon tetrachloride or the lighter petroleum distillates. Such fluids are customarily dispensed in bottles or cans having a removable closure; and in the cleaning operation, a cloth is moistened with the cleaning fluid and rubbed upon the material to be cleaned.

It is the object of my invention to provide in a single article both the supply of cleaning fluid and a cloth or pad through the medium of which the cleaning fluid is applied. A further object of my invention is to produce such a device in which the fire hazard will be minimized when an inflammable cleaning fluid is used. Still another object of my invention is to produce a device of the character described in which the cleaning fluid will not be subject to loss by evaporation or leakage.

In carrying out my invention I employ a container in the form of a bottle or can having an opening at its top, and I cover this opening with an absorbent pad of felt or similar material which is preferably supported upon a rigid cap having one or more holes for regulating the escape of cleaning fluid when the container is inverted. Desirably, between the cap and the absorbent pad there is provided a layer of blotting paper or some similar material which has the property of distributing evenly over the pad the liquid which passes through the cap and which when dry also has the property of sealing the container-opening to prevent loss of the cleaning fluid by evaporation.

In the preferred form of the invention the container, prior to the time it is first placed in use, is completely sealed by one or more members of impervious material which cover the opening at the top of the container, such member or members being of material which can be punctured when it is desired to place the container in use.

The accompanying drawing illustrates two embodiments of my invention: Fig. 1 is a vertical axial section through one form

of the device; and Fig. 2 is a similar section through a modified form.

The bottle 10 illustrated in Fig. 1 is of a shape which while not essential to my invention is convenient because of the fact that it may be readily grasped in the hand and also because its side-walls are convexly curved in such a manner that the bottle will return to an upright position if displaced. The bottle has an upwardly extending neck 11 to the opening in the upper end of which the cleaning pad 12 is applied. The cleaning pad is conveniently a disk of felt or some similar absorbent material.

As a support for the cleaning pad, I may employ a cap 13 of metal or other rigid material which is desirably upwardly convex in order to raise the center of the cleaning pad 12 to facilitate its use. The supporting cap 13 is provided with one or more holes 14 through which the cleaning liquid may escape to the pad 12 when the bottle is inverted, these holes serving the purpose of regulating the escape of cleaning fluid and preventing flow at a rate more rapid than can be absorbed by the pad.

Preferably, there is provided between the pad and the supporting cap 13 a layer of porous material 15, such as blotting paper. This interposed layer of blotting paper performs a double function. In the first place, it receives the liquid which passes through the hole or holes 14 when the bottle is inverted and distributes such liquid uniformly to the pad 12. In the second place, when it dries, it forms an effective closure for the container and prevents evaporation of the cleaning fluid.

For the purpose of retaining the parts at the top of the neck 11 in place, I may provide the neck 11 externally with screw-threads adapted to be engaged by the screw-threads of a collar 16 which has at its upper end an in-turned flange 17 adapted to overlie the peripheries of the pad 12, supporting cap 13, and blotter 15, as is clear from the drawing. Desirably, there is interposed between the top of the bottle-neck 11 and the cap 13 and gasket 18 of any desired compressible material which serves the pur-

100

pose of preventing leakage of the cleaning fluid around the edge of the supporting cap. It will be apparent that by tightening the collar 16 on the screw-threads of the bottle-neck the various parts of the device will be securely clamped in the position illustrated in the drawing.

In the modification of my invention illustrated in Fig. 2, the container is in the form 10 of a metal can 20 having a screw-threaded neck 21 at its upper end. At the upper end of the neck, the metal thereof is turned inward to provide a flange 21' for the support of the absorbent cleaning pad.

15 In this modification, the metal disk 13 is eliminated, and in place thereof I employ a piece 22 of stiff cardboard or similar material which may be covered on both sides with oiled paper or otherwise treated to 20 make it impervious to the cleaning fluid. Above the supporting member 22, is a blotting-paper disk 15, and the cleaning pad 12 is superposed upon this. The desired 25 crowned shape of the cleaning pad may be obtained by the use of a small disk 23 of blotting paper, felt, or other absorbent material which has the function of causing the center portion of the cleaning pad 12 to project upward beyond the top of the sleeve 16, 30 which acts as before to hold the various parts in desired position at the top-container neck.

I contemplate that in the manufacture of the device the container 20 will receive its 35 supply of cleaning fluid, and that after the absorbent pad 12 and the parts which support it have been clamped in place by the sleeve 16 the lower edge of the sleeve will be crimped or otherwise treated to make its 40 attachment to the container of a permanent nature. Thereafter, there will be applied to the container a removable cover or cap 24, conveniently of metal. The device will be marketed in this condition.

45 When it is desired to use the container illustrated in Fig. 2, the cover will be unscrewed to expose the cleaning pad 12, and the supporting disk 22, which previously was imperforate, will be perforated from 50 above with a pin or similar implement to provide an opening through which the cleaning fluid can escape to the blotting paper 15 and therethrough to the cleaning pad 12.

55 This device has several advantages over that illustrated in Fig. 1. In the first place in the condition in which it is manufactured and sold, the container is completely sealed because of the imperforate nature of the 60 supporting disk 22. In the second place the cleaning pad is of a more yielding nature and is more effective.

When not in use, the container rests in the upright position shown in the drawing.

65 As brought out above, the disk 15 of blot-

ting paper serves to prevent loss of any cleaning fluid by evaporation. When the device is to be used, it is grasped in the hand of the user, and inverted, whereupon the cleaning fluid will find its way through 70 the hole or holes 14, will be distributed by the blotting-paper disk 15, and will be absorbed by the felt cleaning pad 12. To hasten the distribution of cleaning fluid to the 75 cleaning pad, the bottle may be shaken or tapped lightly. When the pad 12 has become thoroughly wet with the cleaning fluid, it is rubbed upon the material to be cleaned in the usual manner.

When the cleaning operation is complete, 80 the bottle is returned to its upright position, and the blotting-paper disk 15 dries to prevent any evaporation of the cleaning fluid. The sealing effect of the blotting-paper disk 85 not only prevents loss of the cleaning fluid from evaporation, but also serves to minimize any danger from fire. As a matter of fact, if any cleaning fluid on the pad 12 should become ignited, the flame will be extinguished when the fluid on the pad is consumed, and no damage will be done to fluid 90 in the container.

I claim as my invention:—

1. A container for liquids, comprising a hollow body having an opening at its top, 95 said body being provided adjacent said opening with screw-threads, an exposed absorbent pad covering said opening, and a collar having screw threads adapted to engage those of said body, said collar being provided with an inwardly projecting annular flange adapted to overlie the edges of said pad to retain it in position.

2. A container for liquids comprising a hollow body having an opening at its top, 100 an exposed absorbent pad covering said opening, a collar, and interengageable provisions in said collar and said body for holding said collar in place on said body, said collar being provided with an inwardly projecting annular flange adapted to overlie the edges of said pad to retain it in position.

3. A container for liquids, comprising a hollow body having an opening, at its top, 110 a supporting member overlying said opening, an exposed absorbent pad above said supporting member, an annular retaining member overlying the edges of said pad to hold it in place, said annular member having a central opening to expose the upper 120 surface of said pad, and a disk of porous material between said supporting member and said pad, said disk having a diameter less than the diameter of the opening in said annular member to cause said pad to present 125 an outwardly convex surface.

4. A container for liquids, comprising a hollow body having an opening in its top, 130 a puncturable member covering said opening, said member being of material impervi-

ous to the liquid in the container, an exposed pad of absorbent material covering said member, a collar, means for retaining said collar in position adjacent said opening and 5 overlaying said pad to retain it in position, said collar having an opening to expose the outer surface of said pad, and a disk of porous material disposed between said pad and said member, said disk being of smaller diameter than said member, said disk being of smaller 10 diameter than said opening.

5. A container for liquids, comprising a hollow body having an opening in its top, a puncturable member covering said open-

ing, said member being of material imper-
vious to the liquid in the container, an ex-
posed pad of absorbent material covering
said member, means for retaining said pad
in position, and a disk of porous material 70
disposed between said pad and said mem-
ber, said disk being of smaller diameter than
said member.

In witness whereof, I have hereunto set
my hand at Indianapolis, Indiana, this 15th 75
day of April, A. D. one thousand nine hun-
dred and thirty.

PAUL RUNNELS.
